(57) **CLAIM**

The ornamental design for a vehicle door interior, as shown and described.

DESCRIPTION

FIG. 1 is a perspective view of a vehicle door interior showing our new design;

FIG. 2 is an elevational view thereof; and,

FIG. 3 is a plan view thereof.

The broken line showings of the controls adjacent the armrest, the rectangular element along the bottom and the remainder of the vehicle door are for illustrative purposes only and form no part of the claimed invention.

1 Claim, 2 Drawing Sheets

FIG. 1

FIG. 2

FIG. 3
